UNITED STATES PATENT OFFICE.

WILLIS N. HARTSHORN, OF RACINE, WISCONSIN.

REFINING MACHINE.

1,404,851.

Specification of Letters Patent. Patented Jan. 31, 1922.

Application filed February 21, 1921. Serial No. 446,702.

To all whom it may concern:

Be it known that I, WILLIS N. HARTSHORN, a citizen of the United States, and resident of Racine, in the county of Racine 5 and State of Wisconsin, have invented new and useful Improvements in Refining Machines, of which the following is a description, reference being had to the accompanying drawings, which are a part of this specification.

This invention relates to certain new and useful improvements in grinding and mixing machines, and refers more particularly to that type of machine designed for use in 15 developing and finishing chocolate or the like.

In the manufacture of chocolate, the flavor is developed or improved by an agitating process and at the same time it is desirable 20 to reduce or refine the chocolate, in order to produce the desired smoothness.

Heretofore, the only effective means for producing these desirable qualities have been extremely expensive in cost of 25 machines, have necessitated excessive floor space, have required considerable manual labor and also have necessitated a relatively long period of time in which to complete the process.

With the above in mind, my invention 30 has for one of its objects to provide a machine which combines in a single structure all of the various steps required in the production of chocolate or the like of the required site qualities.

A further object of this invention is to provide a machine of the class described, which will require approximately one-fifth of the floor space now needed for machines 40 at present utilized to perform the various steps necessary to the production of a refined palatable chocolate.

A further object of this invention is to provide a machine of the class described, 45 which not only reduces the amount of floor space necessary to accommodate the same, but one which materially decreases the labor cost of operation.

A still further object of the present invention is to provide a machine of the class described, 50 which includes a grinding or reducing means rotatable in one direction and an agitating paddle mounted above the reducing means, and capable of being either rotated in a direction reversed to the grinding means, permitted to be free and rotate

with the mass as stirred by the grinding means, be held against rotation, or permitted to revolve with the mass at a slower speed.

With the above and other objects in view 60 which will appear as the description proceeds, my invention resides in the novel construction, combination and arrangement of parts substantially as hereinafter described and more particularly defined by the 65 appended claims, it being understood that such changes in the precise embodiment of the herein disclosed invention may be made as come within the scope of the claims.

In the accompanying drawings, I have 70 illustrated one complete example of the physical embodiment of my invention constructed according to the best mode I have so far devised for the practical application 75 of the principles thereof, and in which:

Figure 1 is a view of a machine embodying my invention, parts thereof being broken away and in section to more clearly illustrate the details of construction;

Figure 2 is an enlarged fragmentary view, 80 part in section and part in elevation, said view being taken on the plane of the line 2—2 of Figure 1;

Figure 3 is a view, part in section, part in elevation, taken through Figure 2 on the 85 line 3—3;

Figure 4 is a transverse sectional view taken through the container proper on the line 4—4 of Figure 1;

Figure 5 is a perspective view of one of 90 the grinding member segments, which I employ, and

Figure 6 is a view looking at the inner 95 end of one of the grinding elements or segments.

Broadly stated, my invention may be said to comprise a container, grinding or reducing means within the container, means for agitating the mass within the container to thoroughly aerate the same and at the same 100 time feed the mass to pass between the coacting reducing or grinding surfaces, and means for actuating the grinding and agitating means.

The container is in the form of an outer 105 casing 6, having its uppermost edge directed laterally as at 7 to receive the laterally directed rim or flange 8 of the interior casing or receptacle 9, which is secured in place by a suitable fastening means 10. The receptacle 9 is of less diameter and depth than the outer casing 6, to provide a space for 110

either a cooling or heating fluid and positioned within the space intermediate the bottom walls of the receptacle and casing is a coil 11, having its inlet 12 and outlet 13 connectible with a suitable supply of either a cooling or heating fluid, not shown.

Secured to the top face of the receptacle flange 8 are the lower ends or legs 14 of a substantially H shaped yoke member, the transverse bar or beam 15 of which extends diametrically across the center of the receptacle 9. The upper ends of the legs 14 are formed with axially aligned bearings 16, in which is journaled a drive shaft 17 adapted to be connected with a source of power not shown by a belt trained about a pulley 18 carried thereby, or any other suitable means. The transverse beam 15 is formed with a bearing 19, in axial alignment with the center of the receptacle 9 and has journaled therein the upper portion of a shaft 20, which has its lower end journaled in a thrust bearing 21, carried by the bottom wall of the receptacle 9.

25 Mounted on the upper end of the shaft 20, and concealed within a casing or guard 22 secured to the top of the transverse beam 15 by fastening members 23, is a bevel gear 24, the teeth of which mesh with a pinion gear 30 25 fixed to the drive shaft 17. The pinion gear 25 is also protected by an extension 26, formed on the guard 22.

30 Fixed to the shaft 20, adjacent the bottom of the receptacle 9, is a spider member 27, see Figure 4, which spider is formed with a plurality of radially extending arms 28, having their extreme outer ends formed with transverse lug members 29, which serve to retain the units or segments 30 of a grinding member, which coacts with a grinding surface carried by the bottom of receptacle 9.

35 The grinding member is normally rotated in the direction of the arrow 31, see Figure 4, and materials within the space between the segments 30 are fed by centrifugal force between the grinding member and the grinding surface of said receptacle. Each segment 30 has its under surface radially channeled or grooved as at 32, and the materials thrown outwardly by centrifugal force pass through these grooves, some of it passing beneath the ribs 33, formed by said grooves, and thus being reduced by the grinding action between said ribs and the grinding surface of the receptacle. The segments 30 are loosely secured between the spider arms 28, in order that they may freely conform with any irregularity of the grinding surface of 40 the receptacle 9.

45 In reducing materials similar to chocolate it is essential that care be taken not to overheat the same by permitting excessive friction between the grinding surfaces. 50 From experience I have found that the best

results are obtainable by constructing the grinding segments 30 so that the passages 32 are of greater area than the reducing ribs 33 whereby the flow of material between the grinding elements is substantially 70 unrestricted. While it is primarily desirable that the material be permitted practically free circulation, it is essential that some of the materials pass between the grinding surface in order that they may 75 finally be completely reduced. Therefore I have found that the best results are obtainable by restricting somewhat the flow of material through the channels at their outer ends by making the area of the channels less 80 at their outer ends than at their inner ends, see Figure 6. Such a construction is to be distinguished from the old well known type of grind stone dress in that ready circulation of the material between the grinding 85 member and the grinding surface is permitted and furthermore that only a portion of the material passing between the grinding segments and the container grinding face is subjected to a reducing action. One 90 object sought in chocolate working machines is the agitating with the reducing, but the reducing is not attempted to be accomplished in one operation but is stretched out through the entire agitating period. To do 95 otherwise would overheat the material and gum the grinding surfaces.

95 The material that is passed beneath the segments 30 is directed upwardly by the lugs 29, which have their leading ends extended downwardly and their rear ends extended upwardly. The materials directed upwardly by the lugs 29 are then deflected inwardly toward the center of the receptacle by scraping knives 34 secured to uprights 35 carried by certain of the spider arms 28. The blades 34 have their leading ends preferably engageable with the sides of the receptacle 9 to scrape all materials therefrom that may adhere thereto and have 100 their trailing ends positioned nearer the center of the receptacle whereby the materials will be directed away from the receptacle walls, as will be readily obvious. After the materials have been deflected toward the center of the machine they are conveyed downwardly to the space between the grinding units 30 by means now about to be described. The blades 34, as will be readily apparent, serve to continue the circular 105 movement of the materials along the container walls so that the interruption of the materials may be more abrupt when engaged by the agitator, hereinafter described.

110 Freely rotatable, but non slidably mounted on the shaft 20 is a sleeve 36 to the lower end of which are secured two opposite radially extending agitating paddles 37 and 38, which project into the receptacle to a point 115 adjacent the grinding member. The agi- 120

tator paddles each consist of an inner securing arm 39 from which radially extend horizontal vanes 40, said vanes being inclined upwardly in the normal direction of 5 rotation in order to direct materials downwardly that are engaged thereby. The ends of the vanes 40, carried by each agitator paddle, are connected by a vertical vane 41, which has its leading edge further from the 10 center of the receptacle than its trailing edge whereby the materials thrown in its path by the blades 34 will also be directed inwardly the same time they are being directed downwardly by the vanes 40, to insure 15 the directing of the materials to the space between the segments of the grinding member. In order to obtain more efficient results, the vanes 40 of the agitator paddles are arranged in staggered relation, as best 20 shown in Figure 1.

The agitator paddles are normally rotated in a direction reverse to the direction of the rotation of the grinding member, as best shown by the arrow 42 in Figure 4 25 whereby the movement of the mass of materials within the receptacle, is upwardly toward the top of the receptacle, then inwardly into the path of the vertical vanes 41, then downwardly and into the space between 30 the units of the grinding member, and then outwardly between the co-acting grinding surfaces when the cycle is again repeated, the circular movement of the mass, due to the rotation of the grinding member 35 being abruptly reversed upon its engagement by the agitating paddles, which are rotatable in a reverse direction, thus insuring the thorough co-mingling, aerating and reducing of the materials. The severity of 40 agitation of the mass is capable of regulation, as the agitator paddles are capable of being rotated in the direction of the arrow 42, as above described, can be disconnected from their driving means and either partially 45 or completely held from rotation, or may be released to freely revolve with the mass and thus offer no resistance thereto. I obtain these adjustments of the agitator by the mechanism now about to be described.

50 The lower portion of the legs 14 are connected by a horizontal angle iron 43, which has its part adjacent sleeve 36 curved or struck laterally as at 44 and has secured thereto a bearing member 45, which is in 55 vertical axial alignment with a bearing 46 formed in a bracket member 47 carried by the transverse beam 15. Journaled in the bearings 45 and 46 is a counter shaft 48, and medially secured thereto is a gear 49, which 60 meshes with a gear 50 freely rotatably mounted on the shaft 20.

Gear 50 has a clutch receiving recess 51 formed in its upper face in which is movable the clutch part 52 of a clutch member 65 53, which is slidably, but non rotatably car-

ried by the shaft 20. The clutch member 53 is movable by means hereinafter described to connect and disconnect gear 50 with shaft 20 to rotate gear 49. A second bearing 54 is carried by the bearing member 70 45 and is in vertical axial alignment with a bearing 55 carried by the bracket 47, and journaled in said bearings is a second counter shaft 56. Fixed to the shaft 56, and in mesh with the gear 49, is an intermediate 75 gear 57 and secured to said shaft 56 is a second gear 58 which meshes with a gear 59 made fast to sleeve 36.

By this construction it will be seen that the gear 50, when made fast to shaft 20 by 80 the clutch member 53, rotates gear 49, which in turn revolves shaft 56 through gear 57, rotating the gear 59 through its connection with the gear 58 carried by shaft 56. If desired, the gearing hereinbefore described 85 may be of such a ratio as to have the speed of rotation of paddles 37 and 38 faster or slower than the grinding member 27, depending upon the type of materials for which the machine is especially designed to 90 operate.

The clutch member 53 is actuated by a lever 60, the upper end of which is secured to a shaft 61 journaled in the adjacent leg 14 and a bearing 62 carried by the beam 15. 95 The inner end of the shaft 61 forms one trunnion of a yoke member 63, which has its outer trunnion 64 journaled in a bearing 65, also carried by the transverse beam 15, and said yoke member has its ends 66 100 bifurcated to receive bearing blocks 67 in which are journaled the pins 68 of a ring or collar 69 freely rotatably secured in an annular channel or groove 70 formed in the clutch member 53. With this construction, a movement of the clutch lever in the direction of arrow 71, see Figure 3, will engage the clutch part 53 in the recess 51 and lock the gear 50 with the shaft 20, as a result of which the agitating paddles will 105 be positively rotated in the direction of the arrow 42 through the medium of the gearing hereinbefore described. A movement of the lever 60 in a reverse direction will move the clutch member to its dotted line 110 position in Figure 3 and thus disconnect the agitating paddles from the shaft 20.

115 Should the clutch member 53 be in inoperative position, the agitating paddles are free to be carried by the mass within the receptacle 9, in the direction of rotation of the grinding member, and such being the case, the agitation of the materials will be only slight. As often times it is desired to hold the agitating paddles stationary in order to 120 somewhat agitate the mass or to permit the same to be carried by the mass in its circular movement, but at a less speed, I provide 125 brake means mounted on the shaft 48 and operated by the clutch control lever 60. This 130

brake mechanism consists of a brake drum or wheel 72 secured to the upper portion of shaft 48 and having a brake band 73 engageable therewith, said brake band having one 5 end secured to an adjusting bolt 74 fastened as at 75 to the bracket member 47 and its outer end pivotally secured as at 76 to a lever 77 medially pivoted to said bracket 47 as at 78.

10 The outer free end 79 of the lever 77 has one end 80 of the connecting rod 81 pivotally secured thereto, the outer end 82 thereof being pivotally connected with a crank arm 83 fastened to the trunnion 64 of the yoke member. With this construction, a movement of the lever 60 in the direction of arrow 84, see Figure 3, will commence applying the brake band to the wheel 72 after the clutch is disengaged from the gear 50. This 15 construction forms three active positions for the handle 60, one where the clutch member is in position locking gear 50 to shaft 20 with the brake off, another with the clutch member 53 disengaged from gear 50 and the 20 brake also off, and the third position with the clutch member 53 disengaged from gear 50 and the brake applied to either completely secure the shaft 48, and consequently the 25 agitating paddles against rotation, or to only 30 partially restrain the rotation thereof.

In order that the lever 60 may be releasably secured in any one of its several positions, I provide a quadrant or trace rack 85 with which a clamping or binding member 86, carried by the lever 60, is engageable, and when the lever is in the desired position a binding nut or handle 87 is turned to readily releasably lock the member 86 against the quadrant as will be readily apparent.

35 40 For convenience in discharging the finished materials from the receptacle 9, I provide a discharge spout 88, preferably positioned at the bottom of the container, and said spout is normally closed by a plate or 45 door 89 carried by a lever 90. The lever 90 has one end pivotally secured as at 91 to a bracket 92 secured to the casing 6 and has its outer end movable to engage behind a locking projection 93 carried by said 50 bracket member and when the lever 90 is in its position engaging behind said locking projection, the plate 89 is firmly engaged against the mouth of the outlet by an adjusting screw 94.

55 From the foregoing description taken in connection with the accompanying drawings, it will be readily apparent to those skilled in the art to which an invention of this character appertains that I have provided a machine, which will effectively refine and reduce all types of materials and one in which the grinding surfaces may be of any desired material such as steel or stone according to the desire of the user.

60 65 It will also be obvious that my machine

requires but a minimum amount of floor space for the capacity of material and is capable of operation at a low labor cost, requiring the attention of an operator only at intervals.

70

What I claim as my invention is:

1. In a machine of the class described, a container for receiving the materials to be worked upon, means for rotating the mass of materials in one direction, rotating means for reversing the circular movement imparted to the mass by the first mentioned means, both of said rotating means being capable of simultaneous operation, and means restraining said last mentioned means from rotation.

75

2. In a machine of the class described, a container for receiving the materials to be worked upon, means for rotating the mass of materials in one direction, rotating means for reversing the circular movement imparted to the mass by the first mentioned means, means for restraining said last mentioned means from rotation, and means for permitting said last mentioned means to 90 freely rotate with the mass.

3. In a machine of the class described, a container for receiving the materials to be worked upon, means for rotating the mass of materials in one direction, an agitator 95 disposed above said means, means for rotating said agitator in a direction reverse to that of said means whereby to reverse the circular movement of the mass, means for securing said agitator against rotation, and 100 means for permitting the agitator to freely rotate with the mass.

4. A machine of the class described, comprising a base member having a grinding surface, a grinding member rotatably 105 mounted above the base member and co-acting with the grinding face of the base member to reduce materials passed therebetween, means for directing the materials upwardly as they pass from between said 110 members, movable means for directing the materials inwardly, and means for then directing the materials downwardly to pass between said members.

5. A machine of the class described, comprising a base member having a grinding surface, a grinding member mounted on said base member and co-acting with the grinding surface thereof to reduce materials passed therebetween, an agitator mounted 120 above said grinding member for directing the materials downwardly, means for rotating said agitator, and means for securing said agitator against rotation.

6. A machine of the class described, comprising a base member having a grinding surface, a grinding member mounted on said base member and having a surface co-acting with the grinding surface of the base member, an agitator mounted above said 130

grinding member, a drive shaft, means connecting said grinding member with said shaft whereby said member is rotated in one direction, and a geared connection between 5 said agitator and shaft and operable to cause said agitator to be rotated in a direction reverse to said grinding member and operable to permit the free movement of the agitator independent of said shaft, with 10 the material mass within the machine.

7. A machine of the class described, comprising a base member having a grinding surface, a grinding member mounted on said base member and having a surface co-acting 15 with the grinding surface of the base member, an agitator mounted above said grinding member, a drive shaft, means connecting said grinding member with said shaft whereby said member is rotated in a given 20 direction, a geared connection between said agitator and shaft and operable to cause the agitator to be rotated in a direction reverse to that of said grinding member and operable to permit the free movement of the 25 agitator, independent of said shaft, with the mass of material within the machine, and brake means operable on said agitator to restrain its movement with the mass when the same is disconnected from said shaft.

30 8. In a machine of the class described, a container, grinding means within the container, agitating means cooperating with the grinding means, a drive shaft, means for detachably connecting the agitating means 35 with the drive shaft, and brake means operable only when the agitating means is disconnected from the drive shaft to restrain the rotation of said operating means.

9. In a machine of the class described, a 40 container, an agitating member mounted within the container, a drive shaft, a transmission means for connecting said agitating means and drive shaft and including a clutch member, an operating handle for said clutch member, and brake means operable upon a continued movement of said handle after the clutch member has been disconnected to secure said agitating means against rotation.

50 10. A machine of the class described, comprising a container, a frame work supported above said container, a shaft journaled in said frame work and extending into said container, reducing means mounted on said shaft, a sleeve freely rotatably mounted on said shaft, means for rotating said shaft, agitating means carried by said sleeve and extended into said container, and means operatively connecting said sleeve with said shaft whereby the agitating means will be rotated in a direction reverse to that of said grinding means.

11. A machine of the class described, comprising a container, a frame work supported 60 above said container, a shaft journaled in

said frame work and extending into said container, reducing means mounted on said shaft, a sleeve freely rotatably mounted on said shaft, means for rotating said shaft, agitating means carried by said sleeve and extended into said container, counter shafts journally mounted in said frame work adjacent said first mentioned shaft, and transmission means including gears carried by said sleeve and shafts for connecting said 75 sleeve with said first mentioned shaft to rotate the agitating means in a direction reverse to that of said grinding means.

12. A machine of the class described, comprising a container, a frame work supported above said container, a shaft journaled in said frame work and extending into said container, reducing means mounted on said shaft, a sleeve freely rotatably mounted on said shaft, means for rotating said shaft, 80 agitating means carried by said sleeve and extended into said container, readily detachable means for drivingly connecting said sleeve with said shaft, and brake means operable, only when the sleeve is disconnected 85 from said shaft, to restrain rotary movement of said sleeve.

13. A machine of the class described, comprising a container, a grinding member rotatably mounted in the container, means for 90 directing materials upwardly that have been acted upon by said grinding member, means for deflecting the materials away from the wall of the container, the mass of material deflected inwardly from the container wall 95 100 by said last mentioned means being moved in a circular direction due to the operation of said grinding member, and means for reversing the circular movement of the materials and directing the same downwardly to 105 be again operated on by said grinding member.

14. In a machine of the class described, a grinding member, comprising a hub portion having radially extending arms, transverse projections carried by the outer ends of said arms and segmental grinding members fitted 110 between said arms and restrained from outward movement therefrom by said transverse projections.

15. In a machine of the class described, a grinding member, comprising a hub portion having radially extending arms, transverse projections carried by the outer ends of said arms and segmental grinding members fitted 115 120 between said arms and restrained from outward movement therefrom by said transverse projections, said projections being inclined to direct the materials upwardly that pass outwardly from said grinding member.

16. In a machine of the class described, a grinding member, comprising a hub portion having radially extending arms, transverse projections carried by the outer ends of said arms and segmental grinding members fit- 130

ted between said arms and restrained from outward movement therefrom by said transverse projections, said projections being inclined to direct the materials upwardly that 5 pass outwardly from said grinding member, and means for deflecting the materials inwardly that are directed upwardly by said projections.

17. In a device of the class described, a 10 grinding member having its grinding face provided with a plurality of relatively large grooves separated by relatively narrow grinding edges, the area of said grooves being reduced at their outer ends to restrict 15 the flow of materials therethrough and insure the passage of a greater portion of the materials beneath said grinding edges.

18. In a device of the class described, a 20 grinding member having its grinding face provided with a plurality of relatively large grooves separated by relatively narrow grinding edges, the area of said grooves being reduced at their outer ends to restrict 25 the flow of materials therethrough and insure the passage of a greater portion of the materials beneath said grinding edges, the sides of said grooves opposite the direction 30 of rotation of said member being inclined rearwardly.

19. In a device of the class described, a 35 grinding member having its grinding face provided with a plurality of relatively large grooves separated by relatively narrow grinding edges, the area of said grooves being reduced at their outer ends, to restrict 40 the flow of materials therethrough and insure the passage of a greater portion of the materials beneath said grinding edges and increase the grinding area of said grinding edges.

20. In a machine of the class described, a 45 container having a grinding surface, a grinding member having a grinding surface coating with the surface of said container, means for rotating said grinding member to reduce materials within the container, the rotation of said grinding member imparting

a circular movement to the materials, means for continuing the circular movement of the materials along the container side walls, and 50 means for interrupting the circular movement of the materials set up by the rotation of said grinding member.

21. In a machine of the class described, a 55 container, a reducing member within the container, means for rotating said member to reduce the materials within the container, the rotation of said reducing member imparting a circular movement to the materials, means for continuing the circular 60 movement of the materials along the container side walls, and means spaced from the side walls of the container for interrupting the circular movement of the materials set up by the rotation of said grinding member. 65

22. A machine of the class described, comprising a container, a reducing member rotatably mounted therein, the materials rising after being operated upon by the reducing member, means for deflecting the materials away from the wall of the container, and means for simultaneously directing the materials thrown inwardly from the wall of the container inwardly and downwardly to be again acted upon by said grinding member. 70

23. In a machine of the character described, two telescoping containers of different sizes, means securing said containers in position with their walls in spaced relation to define a chamber for receiving temperature controlling fluids, the inner container receiving the materials to be worked upon, means for rotating the mass of materials in one direction, rotating means for reversing the circular movement imparted to the mass by said rotating means, both of said rotating means being capable of simultaneous operation, and means operable to restrain one of said rotating means from operation. 85

In testimony whereof I affix my signature.

WILLIS N. HARTSHORN.
